Gregory R. Everman

(57) **CLAIM**

The ornamental design for a cover for an electrical outlet, as shown and described.

DESCRIPTION

FIG. 1 is a top front right perspective view of a first embodiment for a cover for an electrical outlet showing my new design;

FIG. 2 is a front elevational view thereof;

FIG. 3 is a rear elevational view thereof;

FIG. 4 is a right side view thereof;

FIG. 5 is a left side view thereof;

FIG. 6 is a bottom plan view thereof;

FIG. 7 is a top plan view thereof; and

FIG. 8 is top, front, right side perspective view thereof shown in use condition.

FIG. 9 is a top front right perspective view of a second embodiment for a cover for an electrical outlet showing my new design;

FIG. 10 is a front elevational view thereof;

FIG. 11 is a rear elevational view thereof;

FIG. 12 is a right side view thereof;

FIG. 13 is a left side view thereof;

FIG. 14 is a bottom plan view thereof;

FIG. 15 is a top plan view thereof; and,

FIG. 16 is a top, front, right side perspective view thereof shown in use condition.

The broken lines showing an electrical outlet are for illustrative purposes only and form no part of the claimed design.
